US0D1026217S

(12) **United States Design Patent** (10) **Patent No.:** **US D1,026,217 S**
(45) **Date of Patent:** **** May 7, 2024**

(54) **MEDICAL INJECTOR WITH HOLDER**

(71) Applicant: **Sensile Medical AG**, Olten (CH)

(72) Inventor: **Milan Kolenda**, Trimbach (CH)

(**) Term: **15 Years**

(21) Appl. No.: **35/516,104**

(22) Filed: **Nov. 4, 2022**

(80) **Hague Agreement Data**

Int. Filing Date: **Nov. 4, 2022**

Int. Reg. No.: **DM/226087**

Int. Reg. Date: **Nov. 4, 2022**

Int. Reg. Pub. Date: **Jan. 27, 2023**

(30) **Foreign Application Priority Data**
